EMERGENCY CALL SYSTEM TRANSMITTER CASE OR SIMILAR ARTICLE

Joseph D. Portanova, Arcadia, and Donald D. Stellmacher, Los Angeles, Calif., assignors to Hoffman Electronics Corporation, a corporation of California

Filed June 28, 1962, Ser. No. 70,727

Term of patent 14 years

(Cl. D72—1)

Fig. 1.

Fig. 2.

Fig. 3.

Fig. 4

Fig. 5

FIGURE 1 is a plan view of an emergency call system transmitter case showing our new design,

FIGURE 2 is a front view thereof,

FIGURE 3 is a side view thereof, shown partially in cross section,

FIGURE 4 is a front view thereof, shown with the front panel open, and

FIGURE 5 is a perspective view thereof, taken from the left rear of FIGURE 2.

The bottom of the case is plain.

The essential features of our design reside in those portions shown in full lines.

We claim:

The ornamental design for an emergency call system transmitter case or similar article, substantially as shown and described.
